RIDING ATTACHMENT FOR A POWER MOWER

Walter A. Kummer, Sheboygan, Wis., assignor of one-fourth to Paul J. Siepmann and one-fourth to Richard A. Siepmann, both of Milwaukee, Wis.

Application July 28, 1955, Serial No. 37,178

Term of patent 14 years

(Cl. D40—1)

FIG. 1

FIG. 2

FIG. 3

Fig. 1 is a side elevational view of a riding attachment for a power mower, embodying my new design;

Fig. 2 is a top view of the riding attachment for a power mower; and

Fig. 3 is a front view of the riding attachment for a power mower, shown in Figs. 1 and 2.

The broken line portion of the drawing disclosure is depicted for illustrative purposes only.

I claim:

The ornamental design for a riding attachment for a power mower, substantially as shown and described.
